WELL PLUNGER AND PACKING

Filed Jan. 3, 1931

UNITED STATES PATENT OFFICE

JOHN W. PIPPIN, OF CORPUS CHRISTI, TEXAS, ASSIGNOR OF ONE-HALF TO H. R. GILES, OF NUECES COUNTY, TEXAS, AND ONE-HALF TO W. F. HALL AND GEORGE LOWREY, OF HARRIS COUNTY, TEXAS

WELL PLUNGER AND PACKING

Application filed January 3, 1931. Serial No. 506,470.

The present invention relates to well plungers and particularly to packing and lubricating means therefor.

The present invention is a continuation in part of my copending application Serial No. 429,189.

An object of the present invention is to provide a well plunger which is equipped with buffing elements so that the working barrel will be polished incident to the reciprocation of the plunger and thereby cause the latter to operate in a smooth manner.

A further object of the invention is to provide means for wiping and oiling the working barrel above and below the lifting cups of the well plunger in order to prolong the wear of said cups and increase the smoothness of operation of the pump.

A still further object is to provide an improved head for the plunger which will provide an unrestricted passage for the upward flow of oil.

Other objects will become apparent during the course of the following detailed description when read in conjunction with the accompanying drawing which forms a part of this specification and in which:

Figures 1 and 1a are continuous views in vertical section of a pump plunger embodying my invention;

Fig. 2 is a cross section of a part of the pump taken on the line 2-2 of Fig. 1;

Referring now more specifically to the drawing, 5 indicates the working barrel in which a pump plunger 6 is reciprocated by a conventional pump rigging including the pump rod 7.

The pump plunger 6 includes a cylindrical ball cage 8 having an interiorly threaded upper end 9 and an interiorly threaded lower end 10. Arranged below the ball cage 8 is a vertically extending conduit or pipe 11 having a circular exteriorly threaded head 12 which is threadedly engaged with the threads 10. The upper face of the head 12 is formed with a seat for the ball valve 13.

A conduit or pipe 14 extends below the conduit 11 and in longitudinal alinement therewith. The conduit 14 is provided with a coupling collar 15 at its upper end which

is threadedly engaged with the lower end of the pipe 11. The usual leather lifting cups 16 and spacer elements 17 are received on the pipe 11 and are held in place by the head 12 and coupling collar 15.

A cup-shaped member 18 is threadedly engaged with the interior screw thread 9 at the upper end of the ball cage 8 and depends within the ball cage. This cup-shaped member 18 is interiorly threaded as at 19 for the reception of the lower end of a vertically extending conduit 20 which has its upper end threaded into a head 21 as indicated at 22. The head 21 is provided with a hollow frustoconical shaped upper end 23 having a plurality of radially disposed outlet openings 24. The outlet openings 24 are disposed outwardly and upwardly in such a manner as to allow practically free passage of the oil from the conduit 20 through the head 21 upwardly through the working barrel. The head 21 terminates in a coupling shank 25 which is threadedly engaged with the lower end of the pump rod 7.

In order to clean and polish the interior of the working barrel above and below the lifting cups 16 during the reciprocation of the plunger, buffing rings 26 are arranged on the pipes or conduits 14 and 20. These buffing rings 26 are preferably formed from any suitable and durable fibrous material or may be composed of a composition of cotton or other permeable felt-like material. The buffing rings 26 are preferably of a diameter slightly greater than the ball cage 8 and have metallic spacer rings 27 received between each buffing ring, the spacer rings having their opposite faces bevelled towards the inner edges thereof.

It will be noted that the lower end of the pipe 15 is threadedly engaged with a collar 29 of the next lower section of the pump plunger, the collar 29 serving to retain the buffer and spacer rings upon the pipe 14.

In order to prevent undue drying of the surface of the working barrel by the buffing rings 26 and thereby cause undue wear of the leather lifting cups 16, means have been provided for lubricating the interior of the working barrel. A plurality of radially dis-

posed vertical slots 28 are formed in the conduits 14 and 20 respectively directly behind the buffing rings 26. These slots 28 allow the oil passing upwardly through the plunger 6 5 to saturate the rings 26 so that they will leave a coating of clean oil on the interior of the working barrel thereby lubricating the same and preventing undue wear on the lifting cups 16.

10 In operation, during reciprocation of the plunger 6, the buffing rings 26 will effectually wipe sand and dirt from the interior of the working barrel and polish the same so as to prevent injury to the lifting cups 16. At the 15 same time, due to the fact that they are saturated with oil which reaches them through the slots 28 the buffing rings will leave a thin coating of oil upon the interior of the barrel thereby insuring smooth operation of the 20 pump and further preventing undue wear upon the lifting cups 16 due to dryness of the barrel.

By providing the hollow head 21 of the plunger with large outwardly and upwardly 25 directed radial openings 24, a free flow of oil is induced due to the fact that little or no obstruction is placed in the upward path of travel of the oil as it emerges from the upper end of the pipe 20. This is considered an 30 important feature of the invention due to the fact that sand and dirt contained in the oil will have less tendency to settle and work down around the sides of the pump as the upward flow of oil is unrestricted.

35 Although a preferred embodiment of the invention has been shown and described, it will be understood that various changes in the details of construction may be made without departing from the spirit of the invention as 40 defined by the appended claims.

What is claimed is:

1. In combination, a pump plunger provided with flexible cups intermediate its ends, a buffing element arranged at either side of 45 the cups for polishing the interior of the working barrel in which the plunger is operating, and means for saturating said buffing elements with oil whereby to lubricate the interior of said working barrel.

50 2. In combination, a working barrel and pump plunger operating therein, said pump plunger having a vertically extending conduit therethrough and being provided with flexible lifting cups intermediate its ends, buffing elements received on said conduit and 55 arranged above and below said lifting cups for polishing the interior of said working barrel, said conduit being provided with radially disposed openings immediately adjacent said buffing rings to permit oil passing therethrough to contact with and saturate 60 said buffing rings whereby to lubricate the interior of said working barrel.

JOHN W. PIPPIN.
